ANTON RAUS, OF CLEVELAND, OHIO.

SINGLE-TRIGGER MECHANISM.

No. 870,318.

Specification of Letters Patent.

Patented Nov. 5, 1907.

Application filed April 24, 1906. Serial No. 313,369.

To all whom it may concern:

Be it known that I, ANTON RAUS, a citizen of the United States, residing at Cleveland, in the county of Cuyahoga and State of Ohio, have invented a certain new and useful Improvement in Single-Trigger Mechanism, of which the following is a full, clear, and exact description, reference being had to the accompanying drawings.

The object of this invention is to provide for double-barreled guns an efficient single trigger mechanism which may be shifted by hand or automatically to discharge the barrels successively in either order, or may be used to discharge either barrel continuously, as desired.

15 My mechanism is particularly adapted for breech-loading guns and is arranged to be automatically set when the gun is opened for reloading.

The various features of the invention are hereinafter more fully described and the essential characteristics 20 set out in the claims.

The drawings show the invention embodied in a double-barreled breech-loading gun, the trigger mechanism being adapted to be shifted by the movement of the releasing lever which allows the barrel to be tipped for loading.

Figure 1 is a sectional side elevation of the lock portion of such gun; Fig. 2 is a vertical cross section on the line 2-2 of Fig. 1; Fig. 3 is a longitudinal section substantially on the line 3-3 of Fig. 1, the barrel 30 being omitted; Fig. 3^a is a vertical cross-section parallel with Fig. 1, being on the line 3^a-3^a of Fig. 2; Fig. 4 is a side elevation of the trigger mechanism; Fig. 5 is a plan of the trigger mechanism; Fig. 6 represents a cross section on the line 6-6 of Fig. 4, showing such parts 35 in five consecutive positions, indicated by the reference letters, A, B, C, D, and E. The remaining figures are perspectives of various parts of the single trigger mechanism, Figs. 8 and 9 representing the same part and showing it in top perspective and bottom perspective respectively.

40 Referring to the parts by reference numerals, 10 represents the stock of the gun and 11 the barrel which is pivoted at 12 to a block 9 carried by the stock.

13 designates the hammers which occupy recesses 45 in the block 9 and are actuated by springs 14 pressing their lower ends rearwardly. A hooked member 15 connected by a bell crank 16 with a hook 17 on the underside of the barrel provides means for cocking the hammers when the barrel is swung on its pivot for loading. 50 When the hammers are cocked, they are engaged by the forward ends of the sears 30 and 31, suitable springs 32 forcing the sears in this direction. To fire the gun, the trigger mechanism raises the rear end of the sears, releasing the corresponding hammer.

55 When the gun is closed the barrel is locked by a bolt 18 engaging a notch in the lug 19, (Fig. 3^a) on the

underside of the barrel. This bolt is connected with the lower end of a lever 21 which is pivoted at its upper end and is connected intermediately by a link 22 with a rock shaft 23, as by an eccentric pin on the 60 lower end of the rock shaft occupying a transverse slot in the link. A spring 25 acting on a cam surface on the rock shaft 23, tends to hold the parts in position with the barrel locked. A lever 24 extends from the upper end of the rock shaft, and when this lever is 65 pressed to one side, the bolt 18 is thereby withdrawn and the barrel is released. In such withdrawal of the bolt an opening 26 therein comes over a spring pressed plunger 27 which, entering the opening, retains the bolt withdrawn, holding the lever 24 in the correspond- 70 ing position.

So much of the construction as is above described is in common use in guns and is not of itself my invention. The releasing mechanism described 75 operates in a peculiar manner with my single trigger mechanism and is herein claimed in combination therewith.

The single trigger mechanism proper includes a trigger 40 and mechanism intermediate of it and the sears so that the operation of the trigger raises one sear or the 80 other, as desired. The trigger mechanism may be shifted by hand so that the single trigger operates either sear, as desired. Automatically shiftable mechanism is also provided to connect the trigger successively with the two sears, and this mechanism is connected with the 85 releasing lever 24 so that every time such lever is operated to open the gun, the trigger connection is shifted back to its initial point. The travel of the trigger mechanism may be either from the right barrel to the 90 left or from the left barrel to the right, as desired, the same being controlled by a suitable button. These parts will now be described.

Secured to the upper side of a plate 41, forming the under side of the lock is a housing 42 in which the trigger 40 is pivoted,—the trigger being of the shape shown in Fig. 13. Pivoted on a vertical pivot extending upwardly from the trigger is a shiftable plate or dog 43, which lies on the upper side of the trigger and over a cross plate 44 carried by the trigger, this dog 43 being adapted to stand beneath either sear and provide a distance piece for raising it when the trigger is raised. A spring 49 acting on the trigger tends to keep it depressed.

The dog 43 is formed with an opening, shown more particularly in Fig. 12 which is occupied by a spring 105 bar 45 secured at one end and carrying at the other end a pin 46. The hole 47 in the dog is occupied by a screw 48 pivoting the dog to the trigger. The pin 46 occupies a hole 50 in the flat bar 51, (shown alone in Fig. 11) which is pivoted at 52 to the trigger. In the rear 110 end of this bar are three V-shaped notches 53, any of which is adapted to be occupied by a plunger 70

mounted in a block 72 secured on the upper side of the plate 41. A spring 73 within a recess in this block and surrounding the shank 71 of the plunger forces the same into engagement with the bar 50. This spring pressed 5 plunger prevents accidental displacement of the bar but allows it to be shifted to shift the pin 46 and swing the dog 43 beneath the corresponding sear. To shift the bar 51 to swing the dog 43 automatically from beneath one sear to a position beneath the other, I 10 provide the following mechanism. Mounted on the upper side of the block 72 and extending into the housing 42 is a plate 60, shown in top perspective in Fig. 8 and bottom perspective in Fig. 9. Formed on the under- 15 side of this plate are two sets of ratchet teeth, each set consisting of two teeth, 61, 62 and 63, 64 respectively. Formed on the upper side of the bar 51 are two ratchet teeth 54 and 55, these teeth facing in opposite directions and being out of alignment with each other. The two sets of teeth on the plate 60 face opposite directions, 20 there being a space between the two sets at least as great as the space the two teeth 54 and 55 together occupy. The bar 60 is capable of a longitudinal movement sufficient to bring either the teeth 61, 62 directly over the tooth 54 or the teeth 63, 64 directly over the tooth 55. 25 In intermediate position, both sets of teeth on the plate are beyond the outer side of the two teeth 54 and 55. This longitudinal movement of the plate is allowed by a slot 65 which the holding and guiding screw 74 occupies. 30 Assuming that the plate 60 is in its rearmost position, as shown in Fig. 1, 3 and 4, the teeth 61, 62 are directly over the teeth 54. If the bar 51 be in its right hand position, the dog 43 will stand beneath the sear 31. This is shown in position A in Fig. 6. If, now, the trigger be 35 raised, the sear 31 is raised, firing the corresponding hammer and bringing the tooth 54 against the incline of the first tooth 62, which shifts the bar 51 sufficiently so that the plunger 70 engages the edge of the intermediate notch 53, forcing the bar into the position shown at B in 40 Fig. 6. The release of the pull on the trigger as the gun is fired allows the parts to come into the position shown at C in Fig. 6, the plunger 70 bringing the bar 51 into the exact intermediate position with its tooth 54 below the second tooth 61. Now the involuntary pull on the 45 trigger which follows the discharge of the gun causes the tooth 54 to engage the tooth 61, shifting the parts into the position shown at D, with the dog bearing against the side of the other sear 30; the spring 45 within the dog being bent sidewise. Then as the trigger is re- 50 leased and the dog lowered, the latter springs under the sear 30, by reason of the resilience of this bar 45 and brings the parts in the position shown at E. In this position the trigger is ready to discharge the left hand barrel. It will thus be seen that the trigger mechanism 55 automatically shifts from one barrel to the other, with the parts as described, this being from the right hand barrel to the left hand barrel.

To return the trigger mechanism to position beneath the right hand barrel, as above described, I provide the 60 following mechanism: Pivoted within the housing 42 on the same pivot on which the trigger is mounted is a bell crank 80 formed as shown in Figs. 4 and 7, and having its longer arm bent upward and extending against the rear end of the bolt 18. The short arm of this bell 65 crank is bifurcated as shown at 81. This bifurcation

takes a link 83 formed as shown in Figs. 5 and 10 and having a hole for the reception of the rear projection formed by the notch 81 of the bell crank. Extending rearwardly from this hole, the link tapers toward a point. This link rests on the inclined shelf 82 of the 70 trigger, and its large end is of such size that it is conveniently guided by the walls of the housing 42. The small end of the link is adjacent to one or the other of a pair of inclines 58 and 59 formed on the bar 51.

Fig. 5 shows the position of the parts after the left 75 hand barrel has been discharged,—this position being the same as that shown at E in Fig. 6. Now when the gun is opened for the extraction of the empty shells and reloading, the first movement of such opening is the swinging of the latch lever 24, and this, drawing rear- 80 ward the bolt 18, moves the bell crank to shove rearward the link 83. In this movement, the link engages the incline 58 and forces the bar 51 into its extreme right hand position, bringing the dog 43 beneath the right hand sear 31, as shown at A in Fig. 6. 85

The above description explains how the sear operating dog passes automatically from the right hand sear to the left hand sear and is automatically returned to the right hand sear when the releasing bolt is operated to open the gun. To change the direction of the operation, so that the sear operating dog shall automatically be moved by the trigger from the left hand barrel to the right hand barrel and be returned to the left hand position by the opening of the gun, I provide the tooth 55 on the plate 51, and the teeth 63 and 64 on 95 the plate 60, as heretofore mentioned. These teeth are idle during the right to left movement of the trigger already described. To bring them into action, the plate 60 is simply shoved forward, this being accomplished by a forward movement of the button 90, 100 (Fig. 3) on the side of the gun stock, which has an arm 91 engaging a pin 67 extending upward from the plate 60. A spring 92 carried by the arm 91 may engage notches in the plate 93 which carries the button to hold it against accidental displacement, and suitable 105 indications as the letters "R" and "L" may be made on this plate,—either being covered by the button 90 and the one visible indicating which barrel of the gun is to be first discharged.

If the button 90 is in its rearmost position, as shown 110 in Fig. 3, the right hand barrel is the one first discharged, as herein first described. If the button is shifted forward, the plate 60 is thereby moved forward and the teeth 63 and 64 come over the tooth 55. These teeth face in the opposite directions to the teeth 61, 62 115 and 64 respectively, and thus the plate 51 and sear operating dog is automatically shifted from left to right.

To cause the return from the right hand position to the left when the gun is opened, the rear end of the link 83 is automatically shifted to come opposite the 120 incline 59, by reason of the bell crank 85, which is pivoted at its elbow on a stud 86 carried by the housing, and carries at the end of one arm a pin 87, which engages a slotted opening 88 in the link 83. The other arm of the bell crank carries a pin or screw 89 which 125 engages in a slot 68 in the edge of the plate 60. The head on the screw 89 holds the bell crank loosely to the plate, and the pin 86 forming its pivot extends through a slot 69 in the plate. Thus when the plate is shifted, the movement of the bell crank correspondingly shifts 130

- the rear end of the link 83. The plate being shifted forward to cause the trigger movement from left to right, the rear end of the link is shifted simultaneously to the right to stand in front of the incline 59, so that 5 when the sear operating dog reaches its right hand position, the opening of the gun automatically returns it to the left hand position.
- The return of the trigger mechanism to its original position whenever the gun is opened is of great advantage, for, in addition to the double barreled firing described, it allows the trigger to be used to fire the same barrel consecutively, if desired. This results from the fact that before a given barrel can be fired a second time the gun must be opened to reload that barrel. It 10 frequently happens that sportsmen retain one barrel loaded for an emergency, the left hand for example, and fire continuously from the right hand barrel,—re-loading it each time. In such case, the trigger mechanism travels across from sear to sear as described, but before the left hand barrel is discharged, the mechanism is returned to the right hand barrel by the opening of the gun. If it is the right hand barrel which is to be held in reserve, the shifting of the button 90 allows the left hand barrel to be fired continuously.
- 20 25 In addition to the automatic shifting of the trigger operating mechanism, it is sometimes desirable that this be done by hand. To accomplish this, I provide a finger lever 95 in front of the trigger, pivoted on a stud of the trigger guard 96. This lever, (shown alone 30 in Fig. 19) has a pin 97 rising from it and extending loosely through an opening 98 in the trigger, and into engagement with an opening 57 in the bar 51. This allows this bar 51 to be shifted by the sportsman's finger engaging the arm 95, whenever desired. This 35 movement is independent of the automatic shifting, and in no way interferes with it. The finger lever 95 also furnishes an indicator, both visible and to the feeling, as to which barrel the trigger is set for.
- When the button 90 is in its mid position, the automatic operation is suspended, for in this position none 40 of the teeth on the bar 51 and the plate 60 engage, and the plunger link 83 stands opposite a recess 99 between the inclines 58 and 59 and operates idly. The finger lever 95 indicates the position the sear operating dog 45 occupies, and may leave it there or shift it to the other barrel, as desired.
- I claim:
1. The combination with a double-barreled gun of a single trigger mechanism including a movable dog adapted to be set for either barrel and having a mid position into which the firing of either barrel brings it, the involuntary pull consequent thereupon shifting it into position for the other barrel.
  2. The combination of a trigger, a shiftable dog mounted thereon, a bar for moving the dog, a plate, co-operative ratchet teeth on the bar and plate to cause the dog to travel crosswise consequent upon the up and down movement of the trigger, and means for automatically returning said dog to initial position when the gun is opened.
  3. In a single trigger mechanism, the combination of a trigger, a shiftable bar mounted thereon, a dog for operating the sears movable by said bar, a shiftable plate, co-operative ratchet teeth on the bar and the plate to cause said bar to move in either direction according to the position of the plate, and means for returning said bar to initial position.
  4. In a single trigger mechanism, the combination of a trigger, a shiftable bar mounted thereon, a dog for operating the sears movable by said bar, a shiftable plate, co-operative ratchet teeth on the bar and the plate to cause said bar to move in either direction according to the position of the plate, and means for returning said bar to initial position.
- ing the sears movable by said bar, a spring pressed plunger for holding said bar in position, a shiftable plate, and co-operative ratchet teeth on the bar and the plate to cause said bar to move in either direction according to the position of the plate. 70
5. The combination of a trigger, a pivoted sear-operating dog mounted thereon, a pivoted bar engaging said dog, a spring pressed plunger for holding said bar in proper position, means operated by the raising and lowering of the trigger to shift said bar laterally, and means for reversing direction of such shifting. 75
6. The combination of a trigger, a pivoted sear-operating dog mounted thereon, a pivoted bar engaging said dog, means operated by the raising and lowering of the trigger to shift said bar laterally, and means for reversing direction of such shifting, and means operated when the gun is opened to automatically return said bar to initial position, said means being automatically shifted when the bar movement is shifted. 80
7. The combination with the sears of a trigger, a pivoted sear-operating dog mounted thereon, a pivoted bar having a spring engagement with said dog, a spring-pressed plunger having a beveled engagement with said bar, means operated by the raising and lowering of the trigger to shift said bar laterally. 85
8. In a single trigger mechanism, the combination of a trigger, a shiftable bar mounted thereon, and having teeth on its upper surface, means for operating the sears controlled by said bar, a member above the bar having teeth co-operative with the teeth of the bar, said member being shiftable to bring its teeth into or out of engagement with teeth on the bar. 90
9. In a single trigger mechanism, the combination of a trigger, a shiftable member mounted thereon, and having teeth on its upper surface, means for operating the sears controlled by said member, a second member having teeth co-operative with the teeth mentioned, one of such members having two sets of such teeth and one of said members being shiftable to bring either set of teeth into engagement with teeth from the other member to cause said shiftable member to travel laterally in either direction as desired. 95
10. In a double-barreled gun, the combination of a single trigger mechanism automatically shiftable from either barrel to the other, an indicator stationary during the shifting for indicating the direction of shift, and an indicator movable with the shifting for indicating the barrel in action. 100
11. The combination, with the sears, of a pivoted trigger, laterally movable mechanism mounted on the trigger and adapted to be shifted in either direction to control either sear, a locking device for the barrel, a member operated by the releasing movement of such locking device, a connection between said member and the sear-operating mechanism, and means for shifting said connection. 105
12. The combination with the sears of operating mechanism therefor, means for automatically shifting said mechanism from either sear to the other, and means for disengaging the automatic operation and leaving either sear as desired in action. 110
13. In a single trigger mechanism, the combination with the sears of operating mechanism therefor including a dog automatically shiftable in either direction to engage either sear, finger-operated mechanism for determining the direction of shift, said dog and mechanism having intermediate positions which disengage the automatic operation. 115
14. In a trigger mechanism, the combination with the sears and the trigger, of operating mechanism automatically shiftable from either sear to the other, mechanism for changing the direction of shift, and a finger device independent of the mechanism for changing the direction of shift, and adapted to shift the operating mechanism in either direction. 120
15. The combination with a double barreled gun of single trigger mechanism automatically shiftable from either sear to the other, means for changing the direction of the shift, such means giving an indication of the selected direction, means operating when the gun is opened to automatically return the trigger mechanism to initial position, and independent finger-operated means to shift the operat- 125
- 130
- 135
- 140
- 145

- ing mechanism as desired without interfering with the automatic mechanism, the position of said independent means indicating which barrel is in action, said finger operated means having a button or engageable part on the under side of the lock plate just in front of the trigger.
16. The combination of sears, a trigger, a laterally shiftable member mounted thereon, a second member, two sets of coöperating ratchet teeth carried by said members to cause the first mentioned member to travel crosswise consequent of its up and down movement, and means for longitudinally shifting the second mentioned member to change the direction of such crosswise movement.
17. The combination with the sears of a trigger, a dog carried thereby adapted to operate either sear, means for automatically shifting said dog from either sear to the other, and means for throwing out of action such auto-

matic operation, whereby the dog may independently operate either sear as desired.

18. The combination with the sears of a double-barreled gun, of sear operating mechanism, means for automatically shifting said mechanism from either sear to the other, means for changing the direction of such shift and for indicating the direction in which the mechanism is set to shift, and means for indicating the particular barrel with which the mechanism is in operation.

20 In testimony whereof, I hereunto affix my signature in the presence of two witnesses.

25 ANTON RAUS.
